Primary Examiner—Lawrence R. Franklin

[57] ABSTRACT

Mechanical counter units each having a plurality of

indicator wheels arranged in successively higher order and commonly mounted on a shaft with other identical counter units are disclosed. A pawl actuator serves to advance the counter are disclosed. A pawl actuator serves to advance the counter wheels through arms engageable with a ratchet on each counter. A keeper in the form of a notch carrying ring on the adjacent lower order wheel prevents engagement of the pawl with the ratchet on the higher order wheel until the next lower wheel has rotated a full revolution permitting the pawl to drop into the notch and engage the ratchet. Resetting means include a bushing keyed to the shaft adjacent an end counter wheel. Transfer washers are disposed between the bushing and the counter wheels and between adjacent counter wheels and serve to interlock the wheels in a reset position when the shaft is rotated. In the preferred embodiment, the counters are arranged in a bank within a common housing which is engaged by a locking tray at the individual counter wheel to prevent inadvertent actuation. The entire counter bank assembly is moved away from the tray to unlock and actuate selected counters.

FIG. 12

1
COUNTER

BACKGROUND OF THE INVENTION

The present invention relates generally to mechanical counters or registers and more particularly to a pawl and ratchet type counter or register especially adapted for use in a voting machine and including a mechanism for positively resetting the counters to the zero position.

Mechanical voting machines are usually equipped with registers or numerical counters, known as tally counters, which register the number of votes cast for each candidate or issue and are actuated by the voter moving the corresponding lever on the machine.

It is general practice for the election officials or judges, when setting up the machines prior to an election, to reset the counting devices in the machine to zero. The counting devices are customarily three digit registers which are reset to zero by a manual operation. For example, it may be necessary to insert a special counter resetting tool into the machine and engage the counters separately, rotating them individually until all the counters are at zero. Obviously, in a voting machine having capacity for a large number of candidates or issues, this is a tedious process subject to inadvertence or error in resetting the counters.

Another problem encountered in voting and like machines using numerical registers or counters is that they are often susceptible to tampering. The reading on the public counters can be fraudulently altered to add or subtract votes from the actual number received by the candidate. Such fraud, if it goes undetected, is a serious interference with the democratic process. Such fraud, if detected, will result in investigations, election contests and recounts, all of which are at the expense of the public and serve to lessen the public's already marginal confidence in the political process.

Therefore, it has been demonstrated that a need exists for a highly reliable counter mechanism adaptable for use in voting machines which can be easily reset and which is not easily susceptible to tampering or inadvertent actuation. The register should be of a substantial design capable of long life without undue wear or need for repair and replacement. Further, a register of the type described should be compact, having a minimum number of parts which can be easily assembled and installed and operate with a high degree of reliability. Finally, the register or counter should include a resetting mechanism which can be easily manipulated and which permits multiple counters to be reset simultaneously.

The present invention provides a counter mechanism which can be mounted on common parallel shafts along with other counter mechanisms of the same design. Each counter comprises multiple adjacent counter wheels, each having a toothed ratchet wheel. Pawl arms activated through cam means serve to selectively engage the ratchet wheel to selectively shift the counter wheels about the shaft to register a vote. Rotation of the mounting shaft causes the counter wheels to be commonly reset to the zero position. The resetting is accomplished through locking washers interposed between adjacent counter wheels which cause the wheels to couple or interlock at an aligned position when the common shaft is rotated.

Further, the present invention makes provision for means that positively lock the counters against inadvertent or fraudulent actuation and shields the counters so

2

that they are generally inaccessible to prevent tampering. The counter wheels are engaged by a locking tray which secures all the counters in position until the main voting lever is actuated. Only then are the counters released for actuation and immediately after actuation they are returned to engagement with the locking tray.

The above and other advantages of the present invention will become more apparent from the description and from the drawings attached hereto in which:

FIG. 1 is a fragmentary perspective view of the counter assembly, the housing being partially broken away to expose the counter mechanism of the present invention;

FIG. 2 is a sectional view through the counter housing along the axis of the counter mounting shaft;

FIG. 3 is a partial sectional view of a counter in a locked position;

FIG. 4 is an enlarged top view of the counter and pawl mechanism;

FIG. 5 is a side view of the counter and pawl mechanism shown in FIG. 4;

FIG. 6 is a detailed front view of a counter wheel;

FIG. 7 is a side view looking toward the left side of FIG. 6;

FIG. 8 is a side elevational view looking toward the right side of FIG. 6;

FIG. 9 is a front view illustrating the counter wheels assembled as a counter unit;

FIG. 10 is a partially exploded view of the principal operating parts of the counter of the present invention; and

FIGS. 11 and 12 are exploded perspective views illustrating the details and operation of the resetting mechanism.

Referring to the drawings in detail, the numeral 10 generally denotes the counter housing assembly which contains a plurality of individual counters or registers 11. Counter housing 10 and the individual counter assemblies 11 included therein would be located, for example, within the confines of a voting machine. For brevity and simplicity, only those parts of the voting machine necessary to an understanding of the invention will be described as the voting machine only serves as one means of actuation of the present invention and per se comprises no part of the present invention. In the event that additional details of the construction and operation of a typical voting machine are desired, reference is made to commonly assigned U.S. Pat. No. 3,524,969, issued to C. M. O'Neal on Aug. 18, 1970.

The construction of the individual counter wheels and counter assemblies is best seen in FIGS. 4 through 8. Referring to those FIGURES, the counter units 11 are of similar construction and a description of a single assembly will apply equally to all. Each assembly includes counter wheels 31, 32, and 33 mounted adjacent one another and rotatable about shaft 25 and accommodated thereon by a bore 28 centrally located in the wheels. The counter wheel includes a main drum or disk member 55. Each drum 55 is generally circular having 10 projecting peripheral surfaces 61 equally spaced and separated by notches 58. Each surface 61 is provided with numerals thereon, the numerals from zero through nine consecutively. The numerals are shown as being slightly raised above surface 61 to permit the numerical readings indicated on the counters to

be recorded by a transfer or contact printing operation onto a permanent record sheet.

As best seen in FIG. 6, one side of the number wheel 55 is provided with a flange which is in the form of an annular ring 56 concentric to the bore 28 at a location radially inward of the base of notches 58. The outer periphery on the ring 56 has a cam groove defined by sides 62 and 64 and corresponding in shape to the space between adjacent ratchet teeth 66 located on the opposite side of the disk. Ring 56 with groove 60 cooperates with the pawl and adjacent ratchet teeth, as will be more fully explained hereafter, to serve as a transfer means between adjacent counter wheels to permit engagement and the advancement of an adjacent higher order number wheel only when the lower order wheel has rotated a complete revolution.

Within its interior, ring 56 defines a recess 72 having a surface 67. Right angle shoulder 68 extends from bore 28 in surface 72, radially aligned with the center of the number surface 61 bearing the numeral 9. The bottom surface 67 of recess 72 tapers in one quadrant, as shown, to the bottom edge of the shoulder 68.

The opposite side of number drum 55 is provided with a ratchet wheel 65 having a series of ten equally spaced ratchet teeth 66 around the periphery of the wheel. Circular hub 69 projects from ratchet wheel 65 concentric to the bore 28 having locking surface 70 thereon. A shoulder 71 extends radially toward the projected center of the surface bearing the numeral 4 across surface 70. One quadrant of surface 70 is tapered to the bottom of shoulder 71. Locking surface 70 cooperates with locking surface 67 of the adjacent counter to reset the counters as will be explained hereafter. For economy and weight reduction, the counter wheels are preferably formed of a light plastic such as polycarbonate or other resin in a molding operation. Having described the construction of the individual number wheels, reference will be had to FIGS. 4, 5, and 10 for understanding of the operation of the counter unit.

Assembly 11 is mounted for rotation upon shaft 25 and includes counter wheel 31 and identical counter wheels 32 and 33 arranged in sets of three, or any other desired number to form a counter unit and ascending in order from right to left. Counter wheel 31 occupies the unit space, 32 in the tens, and 33 in the hundreds. The counters are assembled with hub 69, for example, of wheel 33 engaged within the circular recess 72 of the adjacent number wheel 32 so that ratchet wheel 65 of counters 32 and 33 are directly engaging rings 56 of counters 31 and 32. It will be seen that the outer diameter of the circular ring 56 is slightly greater than the matching diameter of the tip of the teeth of ratchet wheel 65. A thrust washer 75 is inserted between the bottom of recess 72 and surface 70 on hub 69 to facilitate the resetting of the counters as will be more fully explained hereafter.

During the registering operation, the individual counter wheels are shifted through a pawl assembly 24. The corresponding pawl assembly for each counter assembly is mounted on a parallel shaft adjacent the associated counters. For example, the pawl assemblies on shaft 26 are adapted to actuate the counter assemblies 11 on adjacent shaft 25. The pawl mounted on shaft 40 serves to actuate the counter on the next successive shaft. Each pawl assembly 24 includes pawl carrier member 36 which is rotatable about its mounting shaft.

Extending towards the counter assembly from carrier 36 are members 38 and 39 which support pawl shaft 40. At one end of the carrier 36 is actuation arm 43 having recess 44 therein to assure positive actuation of the pawls. The pawl assemblies 24 are positioned on their respective shafts with end 43 accessible through openings 19 in panel 12 so that actuation rods 22 can depend into recess 44 of the cam surfaces. One actuation rod is shown in FIG. 1, it being understood that 10 one is provided corresponding to each pawl and counter assembly.

Pivottally mounted on shaft 40 of pawl carrier 36 are individual pawl arms 47, 48 and 49 which extend forwardly and each terminates in notched end 50. The notched end 50 of pawl arm 49 engages ratchet wheel 65 of counter wheel 31. When pawl carrier 36 is rotated about its shaft away from the counter wheel, the pawl arms will retract, causing the engaged counter wheels to shift.

The notched ends of pawl arms 47 and 48 extend, respectively, between counters 32 and 33, and 31 and 32, and are in selected engagement with the ratchet teeth of wheels 32 and 33. The width of pawl arms 47 and 48 exceeds the width of ratchet teeth 66 so that arms 47 and 48 occupy almost the entire space between the ratchet wheels. Thus, it will be seen that the notched end 50 of pawl arms 47 and 48 will not be permitted to engage the ratchet wheel of counters 32 and 33, except when adjacent wheels 31 and 32 are shifted so that cam notch 60 in flange 56 of the respective wheels permits end 50 to drop into and engage teeth 66. Thus, flange 56 serves as a transfer mechanism to the higher order counter wheels by means of which an adjacent higher order wheel will be shifted by the pawl arms only when the adjacent lower order wheel has completed a full revolution. Unit wheel 31 is always engaged and will be actuated whenever pawls retract, while higher order wheels 32 and 33 are intermittently actuated.

It will be observed that each of pawl arms 46, 48, and 49 are independently hinged to shaft 40 at hubs 41. Hubs 41 are formed each having opposite approximately semi-circular extensions 98 and 99 at either end of the hub so that adjacent hubs interlock as seen in FIG. 4. A small clearance space 100 is provided at the interlocking surfaces. In this way, each pawl arm is permitted some downward freedom of movement, but will pick up the next adjacent higher order pawl arms when upwardly displaced. For example, pawl arm 48 can drop into its associated notch between the counter wheels 31 and 32 without moving arms 47 and 49. However, when the surface at 56 lifts arm 48, arm 47 will be interlocked and also caused to raise. This prevents any inadvertent actuation of the next higher order wheels.

A retainer in the form of a spring 52, FIG. 5, is provided to bias the pawl arms toward their respective ratchet wheels and maintain contact. Spring 52 has upper fingers 53 which extend along the upper surfaces of pawl arm 47, 48, and 49. Springs 52 are secured around pawl carrier 36 and compressed against the pawl fingers by engagement with the underside of panel 12. Lower fingers 51 terminate in detents 54 which engage notch 58 in each of the counter wheels to retain the wheels from being rotated through frictional contact with an adjacent actuated wheel.

Although the counter mechanism 11 can be used singly in an application such as a counter for a machine

tool, the counters of the present invention are particularly adaptable for an arrangement as seen in FIG. 1, having multiple counters in a single housing. Housing 10 is provided with upper panel 12 which is generally planar, having cut-out window sections 13 at locations corresponding to the location of the counter mechanisms 11 through which the counters can be viewed. Openings 19 in panel 12 provide access to the pawl actuating cam 43 to permit insertion of an actuation lever 22, which, for example, would be linked to a voting key in a voting machine.

As seen in FIG. 2, the body of housing 10 is in the form of a tray having staggered parallel rib sections 14 between which the individual counter assemblies 11 are mounted. The housing tray can be made of any suitable material. However, for strength and lightness, molded construction of a plastic, such as polyurethane, is preferable. Access to the counter housing would generally be through a removable cover plate in the voting machine which would be sealed after the machine is serviced for an election.

Immediately subjacent housing 10 is locking tray 20. Locking tray 20 has a plurality of semicircular indentations 21 which correspond in location and shape to the counter assemblies. FIGS. 2 and 3 show the counters tightly received in indentations 21 in a locked position with ridges 23 therein engaging peripheral notches 58 on the individual counter wheels. Since the outer periphery of the counter assemblies 11 is tightly engaged against the surface of indentations 21, they cannot, in this position, be rotated. Thus, a positive lock against inadvertent actuation is provided. Similarly, once the voting machine is readied for an election, the locking tray blocks access to the counters without dismantling the machine, thereby effectively discouraging intentional tampering with counters.

The locking tray 20 is fixed and housing 10 is hinged through a cam lever 17 which is pivotal to raise the housing 10 into or out of engagement with the tray 20. By rotation of cam lever 17, housing 10 is caused to raise to disengage from the counter and is then shifted leftwardly as shown by the arrow, looking at FIG. 1, to actuate the counters. Upon completion of the cycle, housing 10 returns to its locked position. The drive means and linkages for actuating lever 17 and reciprocating housing 10 are not shown as any number of conventionally known mechanisms can be used and further description is not deemed necessary to a complete understanding of the present invention.

The operation of the counter described herein will be apparent from the following description with the tray 20 tray assembly installed in a conventional mechanical lever type voting machine in which a counter is provided corresponding to each selection lever on the machine. When the voter has made his selection, depressing the appropriate keys on the machine, he will cause through linkages (not shown), blocking rods 22 corresponding to the selections to move downwardly through access openings 19 in panel 12 into engagement with positive recess means 44 of cam surface 43. When the voter has completed making all his selections, he will throw the main vote registering lever which will actuate counter housing 10, causing cam lever 17 to pivot, moving housing 10 out of engagement with tray 20.

As the housing 10 moves to the left, pawl carrier 36 will be rotated as the end of rod 22 engages recess 43.

The rotation of carrier 36 retracts pawl fingers 47, 48, and 49 which are held adjacent their respective counter wheels by biasing spring 52.

Assuming the counter is registering 009, as shown in FIG. 9, when the actuation cycle begins, pawl 49 will be in engagement with a tooth 66 of ratchet wheel 65 of counter wheel 31. Pawl 48 will drop into surface 64 of notch 60 formed in flange member 56. As actuation cam 43 causes the pawl fingers to be actuated, the notched end 50 of pawl 48 will engage shoulder 62 in annular ring 56 and will also simultaneously engage a ratchet tooth 66 of adjacent counter wheel 32. Thus, as the pawl fingers 48 and 49 are retracted, both counter wheels 31 and 32 will be rotated through one-tenth of a revolution. Counter wheel 31 will advance, rotating the zero into position under counter window 13 and higher order counter wheel 32 will be advanced to cause the zero reading to be replaced by the digit 1. On the next subsequent actuation of cam 43, again pawl fingers 47 and 48 will be kept out of engagement with the gear teeth 66 on counter wheels 32 and 33 by virtue of flange 56 on the left side of counter wheels 31 and 32. Counter wheel 32 will not be caused to rotate until counter wheel 31 has again advanced to indicate a digit 9 appearing thereon. Similarly, as described above, when the reading 99 appears on counters 31 and 32, all three counter wheels will be permitted to advance one-tenth of a revolution on the next actuation thereby registering the number 100 as both wheels 31 and 32 will have advanced to where pawl fingers 47 and 48 can engage their respective ratchet wheels. Thus, the annular flange 56 between adjacent counters serves as an integral part of a transfer mechanism controlling the actuation of the higher order wheels.

As previously stated, one essential feature of this invention is the provision of an improved resetting mechanism which allows all the counter assemblies on a common shaft to be commonly reset. In this way, the resetting function is rendered more convenient for the operator not requiring a multiplicity of repetitive steps.

As described above, the complete counter assembly includes a series of counter wheels 31, 32, and 33 commonly mounted on a shaft. Resetting is accomplished by rotating the shaft in the direction of the pawl actuation, as indicated, causing end counter wheel 33 to rotate therewith by means of a drive bushing 80 and thrust washer 75. A pick-up coupling between the wheels, including washers interposed between adjacent counter wheels in cooperation with coupling or locking surfaces on the adjacent wheel surface, causes the wheels to progressively interlock in resetting alignment as will be explained.

FIGS. 10, 11, and 12 best show the assembly of the counter unit and the components of the resetting mechanism. Main drive shaft 25 is provided with an axially extending flattened portion 79. A circular drive bushing 80 mounted thereon has a central bore 81 to accommodate the shaft which corresponds in shape to the cross-section of the shaft, and, therefore, will be caused to rotate with the shaft when shaft 25 is rotated through knob 27. Drive surface 82 of bushing 80 is generally planar having a reduced depth locking segment 84 formed in one quadrant of the surface. A right angle lip 83 and a taper lip portion 88 extend from lower locking surface 84 to surface 82 of drive washer 80.

Drive bushing 80 is received within recess 72 of wheel 33 as set forth above. The bottom of recess 72 is formed having a radial lip 68 extending from the circular bore 63 radially to the outer edge. The surface 67 of recess 72 is generally planar but is tapered gradually in one-quarter of the surface to the lower edge of depression 68.

Interposed between drum bushing 80 and locking surface 67 of counter wheel 33, completing the coupling, is thrust washer 90. Thrust washer 90 is a thin, deflectable circular member corresponding in diameter to bushing 80 and having peripheral tabs 92 and 93 formed therein. Tab 92 is bent to project above the surface of washer 90 and tab 93 is oppositely bent to project below the surface of the washer as seen in FIG. 11.

Upon normal registering operation, counter wheel 33 rotates and washer 80 remains stationary. Tab 93 on thrust washer 90 extending toward counter wheel 33 will simply be depressed by surface 67 as rotation occurs and no locking engagement will occur. Similarly, thrust washer 90 will be permitted to rotate relative to stationary lock washer 80 as tab 92 will be depressed by drive surface 82 and not fall into locking engagement with shoulder 83 of washer 80.

In order to reset the number wheels, shaft 25 is turned with knob 27 located at the outer end of the shaft adjacent the edge of housing 11. Rotation of shaft 25 in the resetting direction shown will impart rotation to washer 80, since bushing 80 is keyed to the shaft by flat 79. As bushing 80 rotates, shoulder 83 will engage the end of tab 92, thereby causing thrust washer 90 to rotate along with bushing 80. As bushing 80 and washer 90 rotate together, tab 93 of washer 90 will engage shoulder 68 on surface 69 of wheel 33, thereby picking up wheel 33 and causing it also to rotate.

Rotation of wheel 33 will, in turn, be imparted to adjacent counter wheel 32. As seen in FIG. 12, the side of wheel 33 opposite washer 80 is provided with an annular hub 69 extending outwardly from ratchet wheel 65. Hub 69 is provided with a tapered notch which terminates in radial edge 71. Thrust washer 90, identical to the washer described above, is placed adjacent the hub on shaft 25. The thrust washer 90 and hub 69 are received in recess 72 of the adjacent counter 32. Recess 72 in counter 32 is provided with locking surface 67, also as described above.

Thus, as counter wheel 33 is caused to rotate through the manual actuation of shaft 25, adjacent counter wheel 32 will be imparted rotation. Counter wheel 33 will rotate until shoulder 71 engages tab 92 of thrust washer 90, causing it to rotate along the counter wheel. Thrust washer 90 will rotate opposite tab 93 into engagement with shoulder 68 of counter wheel 32. Counter wheels 33 and 32 are then in locked rotational alignment. It will be noted that thrust washer 93 is constructed with tabs 92 and 93 oppositely extending and diametrically opposed. Similarly, notch 71 on surface 70 of counter wheel 33 and notch 68 on surface 67 of counter wheel 32 are spaced 180° apart with reference to the numerals appearing on the periphery of the wheels. By virtue of this relationship, coupling engagement between adjacent counter wheels will occur when the numerals on wheel 33 are aligned with the identical numerals on corresponding counter wheel 32.

Similarly, the locking surfaces on adjacent counter wheels 32 and 31 will become engaged through inter-

posed thrust washer 90 so that counter wheel 31 will be picked up and locked in rotational alignment with counter wheels 33 and 32. All three of the counter wheels are now aligned and rotation of knob 27 will be continued until the reading 000 appears in windows 13 of housing surface 11. It will, of course, be obvious that any number of counters could be commonly arranged on shaft 27 and that they would be successively locked in alignment by the reset mechanism described above. The assembly of the counters and locking on adjacent shaft 26 is identical with that described with reference to shaft 25. Note also that in FIG. 1, the knob 27 in the outer ends of shafts 26 has been omitted for clarity.

It is believed that the apparatus will be fully understood in light of the above detailed description and summary of the sequence of operation of the counter when used in connection with a voting machine. Because of the positive locking mechanism provided, the counters have particular applicability to use in connection with voting machines but, of course, can be used singly or in multiple groups in a wide variety of applications such as odometers, timing devices and the like. The counter assembly can be used without the locking tray and independently thereof. Also, the counters can be used without the resetting mechanism described above. Similarly, the resetting mechanism described above can be used in connection with counter wheels of a construction other than that described herein. Thus, the present invention provides a counter registering mechanism and a resetting mechanism which are highly accurate and reliable and which can easily be fabricated by well-known conventional stamping and molding techniques. Various parts of the assembly are relatively simple and assembled in an uncomplicated manner to provide a high degree of reliability. Such reliability is particularly important when used with the voting machine as a malfunction could require recounts or election contests which can be expensive and time-consuming.

While a preferred embodiment of the invention is shown in the drawings and described above, it will be obvious that various changes may be made in the form, structure and arrangement of the parts without departing from the spirit of the invention.

What is claimed is:

1. In a voting machine having multiple selection mechanisms, a counter mechanism comprising:
50 a housing member having multiple aligned openings therein and carrying at least two parallel spaced apart shafts,
a plurality of counter indicating assemblies in registry with the openings and rotatable about one of said shafts,
said housing and indicating assemblies adapted for movement to an actuation position in response to actuation of the selection mechanisms,
each of said assemblies having a plurality of numeral wheels rotatably mounted to said one shaft including a first wheel for indication of the units digit and succeeding wheels spaced apart and arranged in ascending order, each of said drums being numbered on the periphery from 0 through 9 successively,
ratchet wheels in the form of gear teeth affixed to one side of each of the numeral wheels,

a pawl carrier mounted on the other of said shafts adjacent said counter assembly and having cam means thereon,

a first pawl arm operatively connected to said pawl carrier and having a notched end engaged in the ratchet means associated with said first wheel whereby actuation of said cam will shift said first pawl means thereby rotating said first wheel by one digit,

second pawl arms operatively connected to said pawl carrier and having notched ends each adapted to engage the ratchet wheel of one of the higher order wheels,

a generally annular surface on each wheel opposite the ratchet teeth and adjacent the ratchet teeth of the next higher order wheel, said surface adapted to keep said second pawl means out of engagement with the associated ratchet cam means in said surface permitting the notched ends of said second pawls to engage the associated gear only when the next successive lower order wheel has assumed a predetermined rotative position,

hub means interconnecting said first and second pawl arms for serially interlocking said pawl arms, whereby each of said second pawl arms is allowed to move to said position of operative engagement only if the next lower order pawl arm is in a position of operative engagement,

a locking tray having indentations therein corresponding to the counter assemblies, said locking tray engaging the periphery of the counter wheels in a non-actuated position,

lever rod means each associated with and responsive to one of said selection mechanisms and adapted to move into actuating relationship with said pawl arm cam means in response to actuation of said selection mechanism, and

actuation means for moving said housing and said assemblies from engagement with said locking tray to said actuation position thereby actuating said pawl arm cam means engaged by said rods to actuate said assemblies and register voters selections.

2. The apparatus of claim 1 further including means for resetting the counters commonly mounted on the same shaft.

3. The apparatus of claim 1 including spring means engaging said first and second pawl arms biasing said pawl arms toward engagement with their respective associated ratchet wheels and detent means engaging said counter wheels to constrain said wheels against actuation except by the associated pawl.

4. The apparatus of claim 1 wherein said cam means mounted on said pawl carrier is provided with a recess therein adapted to receive the end of an actuation rod thereby providing said pawl carrier with position two-way actuation upon reciprocation of said housing.

5. A counter comprising:

a shaft,

a plurality of counter wheel members rotatably mounted about said shaft including a first wheel for indication of the units digits and succeeding wheels spaced apart arranged in ascending order, each of said wheels being numbered on the periphery from 0 through 9 successively,

ratchet wheels in the form of gear teeth affixed to a first side of each of the numeral wheels,

a pawl carrier mounted adjacent said counter wheels and having cam means thereon responsive to operator actuation to pivot said pawl carrier,

first pawl arm operatively connected to said pawl carrier and having a notched end engaged in the ratchet wheel associated with said first counter wheel whereby actuation of said cam will shift said first pawl means thereby rotating said first counter wheel to advance said first counter wheel by one digit,

second pawl arms operatively connected to said pawl carrier and having notched ends extending into the spaces between successive counter wheels and engageable with the ratchet wheels associated with the successive counter wheels.

disengagement means including a generally annular surface associated with the counter wheels and extending into the spaces between said counter wheels adjacent the ratchet wheel on the next adjacent counter wheel, said surface adapted to keep said second pawl means out of engagement with the associated ratchet wheel, and cam means in said surface permitting said notched ends of said second pawls to engage their associated ratchet gear wheel only when the next adjacent lower order counter wheel has assumed a predetermined rotative position, and

articulated hub means having interlocking surfaces for operably interconnecting adjacent pawl arms at said pawl carrier whereby each pawl arm is moveable into engagement with said one of said ratchet wheels independent of the other pawl arms but when moved out of engagement with its associated ratchet wheel will interlock and move the next higher order pawl arm out of engagement with its associated ratchet wheel.

6. The counter of claim 5 including biasing means biasing said first and second pawl arms toward engagement with their respective ratchet gear teeth.

7. The counter of claim 5 including resetting means whereby rotation of said shaft in a predetermined direction will reset the counter wheels so that the same numeral is aligned on all said wheels.

8. The counter of claim 5 wherein multiple counters are arranged on a common shaft to form a counter tray and further including locking means, said locking means comprising a locking plate adapted to engage the periphery of the counters in a locked position and means for selectively moving said counter tray to an unlocked actuating position.

9. The counter of claim 8 wherein said locking means comprises means engaging the periphery of said counter wheels to prevent movement, said locking means and said counters being moved apart to release said counters.

10. The counter of claim 5 including locking means adapted to lock said counters against actuation except when said locking means are released during the actuation sequence in response to proper operator actuation.

11. The counter of claim 10 wherein multiple counters are commonly arranged on said shaft and the corresponding pawl carriers for the multiple counters are arranged on a parallel shaft.

12. The counter of claim 11 wherein said counters are arranged in a voting machine and said actuation comprises a voting operation wherein selections are

made and further including lever rod means adapted for interconnecting said voting machine and said counters whereby actuation of said counters is initiated through actuation of a main voting control to register said votes on said counters.

13. A counter comprising:

a plurality of adjacent indicating wheels arranged in successively higher numerical order and rotatable about a shaft and each provided with a sequential series of indicia thereon,
 ratchet means associated with each of said indicating wheel,
 pawl means adapted to engage said ratchet means, said pawl means having a first pawl arm in engagement with the first ratchet means associated with the lowest order wheel and second pawl arms forming a connection with the ratchet means on the successive higher order wheels,
 means operative with said pawl means to move said pawl means through an actuation cycle causing said first pawl arm to engage said first ratchet means and rotate said lowest order wheel and said second pawl arms to move to a position of operative engagement with the ratchet means on said higher order wheels,
 cam means adapted for disengagement of the second pawl arms with the next higher order ratchet wheel

except when the adjacent lower order wheel has completed a revolution, and
 hub means interconnecting said pawl means for serially interlocking said pawl arms, whereby each of said second pawl arms is allowed to move to said position of operative engagement only if the next lower order pawl arm is in a position of operative engagement.

14. The apparatus of claim 13 wherein said indication wheels are rotatable numeral wheels sequentially numbered 0 through 9 around the periphery and wherein said cam associated with said wheels permits actuation of the next higher order wheel only subsequent to when said adjacent lower order wheel has registered the number 9.

15. The counter of claim 13 including means for commonly resetting the indicating wheels to zero.

16. The counter of claim 13 wherein said hub means comprises a hub on each pawl arm with interlocking surfaces between adjacent pawl arms.

17. The counter of claim 16 wherein said interlocking surfaces between adjacent pawl arms comprise a semi-circular extension on the hub of one adjacent pawl arm mating with a semi-circular indentation on the hub of the other adjacent pawl arm.
